PRINTERS' FURNITURE

Edward M. Heinz, Sr., 136 W. John St., Hicksville, N.Y.
Filed Nov. 2, 1959, Ser. No. 850,125
6 Claims. (Cl. 101—402)

This invention relates to printers' furniture and refers more particularly to spacers used by printers in setting up printing plates.

An object of the present invention is the provision of expandable furniture which can be conveniently extended and adjusted, so that one piece of furniture can be effectively used to fit a variety of different spaces.

Another object is the provision of expansion furniture which can be easily adapted to fit very large, as well as very small spaces, and which can be locked effectively at precisely the desired space.

A further object is the provision of expansion furniture which is extremely accurate and will retain such positive accuracy despite most excessive locking up strains or quoins pressure.

Yet another object of the present invention is the provision of expansion furniture which is light in weight, while being very strong and completely rigid, and which will not rust or tarnish despite adverse conditions.

Other objects of the present invention will become apparent in the course of the following specification.

In accomplishing the objects of the present invention it was found desirable to provide a furniture piece having two interengaging movable parts, so that the piece can be expanded or contracted to fit any required space. The parts of the furniture piece may be provided with serrations serving as a scale, as well as effective locking means.

A furniture piece constituting one embodiment of the inventive idea is suitable for widths from about 3 ems to about 12 ems and consists of an outer part having recessed side walls and a bottom consisting of two spaced plates provided with opposed channels. The inner part has a middle section fitting between the two bottom plates and provided with ridges located in the channels. The inner part also has side sections sliding in the recesses of the side walls of the outer part.

Another embodiment of the present invention pertains to a furniture piece suitable for a narrow width of approximately one to five picas; this piece consists of an outer part serving as a casing for an inner part provided with a T-shaped head.

Furniture pieces constructed in accordance with the present invention are preferably provided with serrations which are so arranged that the furniture is expandable by one pica step. The locking of the movable parts is preferably effected by a thumb screw or a cam lock.

The invention will appear more clearly from the following detailed description, when taken in connection with the accompanying drawing showing, by way of example only, preferred embodiments of the inventive idea.

In the drawing:

FIGURE 1 is a top view of a furniture piece constructed in accordance with the principles of the present invention.

FIGURE 2 is a side view thereof.

FIGURE 3 is a transverse section along the line 3—3 of FIGURE 1.

FIGURE 4 is a sectional view illustrating a lock of a different type.

FIGURE 5 is a side view of a differently constructed furniture piece.

FIGURE 6 is a section along the line 6—6 of FIGURE 5.

The printers' furniture piece shown in FIGURES 1, 2 and 3 of the drawings includes an outer member 10 and an inner member 11. The outer end member 10 has a

2

registering end surface 12, while the inner member 11 has a registering end surface 13. Since the inner member 11 slides within the outer member 10, it is apparent that the distance between the registering surfaces 12 and 13 can be adjusted, depending upon the space which must be filled by the furniture piece.

The outer member 10 has a recessed side surface 14 which is enclosed on three sides by a top flange 15, a bottom flange 16 and an end flange 17. The fourth side is open to enable the sliding of the inner member 11. The opposite side of the outer member 10 is similarly shaped and has a recessed side surface 18 enclosed by a top flange 19, a bottom flange 20 and an end flange 21. The top of the outer member 10 is again enclosed on three sides by upwardly extending flanges, consisting of a side flange 22, another side flange 23, and an end flange 24 which joins the flanges 17 and 21. The bottom of the outer member 10 is of the same construction and is enclosed by two side flanges 25 and 26 and an end flange 27.

The bottom of the outer piece 10 consists of two bottom portions 28 and 29, which extend parallel to each other and which are joined by a connecting member 30, the outer surface 12 of which constitutes the registering surface of the outer member 10. It is apparent that the connecting member 30 is integral with the top and bottom flanges 24 and 27.

The bottom portions 28 and 29 extend parallel to each other and form therebetween a slot 31 which extends across the entire outer member 10 and substantially 30 throughout the entire length thereof. Two pairs of opposed longitudinal grooves 32 to 35 are formed in the opposed surfaces of the bottom portions 28 and 29.

It is thus apparent that in general appearance the outer member 10 has the shape of an elongated container provided with an open top and an open bottom. In cross section the outer member 10 has the shape of the letter U extending above an inverted U.

The inner member 11 is essentially complementary to the outer member 10. It has a rectangular end piece 36 provided with the above-mentioned registering end surface 13. Two sides 37 and 38 are firmly connected with the end piece 36. The side 37 slides within the recessed side 14 of the outer member, and is enclosed by the flanges 15 and 16 of the outer member.

As shown in FIG. 3, the outer surface of the side 37 is flush with the side surfaces 15 and 16 of the outer member 10. Due to this arrangement the furniture piece composed of the outer and inner members 10 and 11 presents an uninterrupted side surface which facilitates the insertion of the furniture piece by the printer. The side 38 is similarly constructed and slides in the recessed side 18 of the outer member 10. The side 38 is also enclosed by the flanges 19 and 20, so as to present a smooth uninterrupted surface. When the furniture piece is completely collapsed, so that it has its smallest length, the ends of the sides 37 and 38 will engage the flanges 17 and 21 of the outer member 10, so that smooth, uninterrupted surfaces are provided. The inner member 11 has a bottom portion 39 which is integral with the sides 37 and 38, and which extends through the slot 31. This bottom portion 39 has two pairs of opposed ridges 40, 41, 42 and 43. As shown in FIG. 3, the ridge 40 fits into the groove 32, while the ridge 41 fits into the groove 34. Similarly, the ridge 42 fits into the groove 33, while the ridge 43 fits into the groove 35.

The bottom portion 39 of the inner member 11 is also provided with an elongated centrally located slot 44, the ends of which are spaced from the ends of the inner member 11.

While in the above description the outer and inner members 10 and 11 were described as having a bottom and a

top, it is apparent that they are essentially of the same construction both at the top and the bottom, so that they can be conveniently reversed in use.

One of the edges of the slot 44 is provided with serrations 45 which serve as a scale graduated in pica or in any other suitable manner. The serrations 45 cooperate with correspondingly spaced projections 46 (FIG.3) which are provided upon the under surface of the bottom portion 28. The arrangement is such that the members 10 and 11 may conveniently slide relatively to each other, but their sliding movement will be stopped or impeded when a projection 46 fits into one of the serrations 45.

The members 10 and 11 can be firmly clamped relatively to each other by means of a thumb screw 47, which is mounted upon a bolt extending through a suitable opening provided in the bottom member 28. The bolt extends through the slot 44 of the member 11 and is carried by a preferably square piece 49 which fits into a corresponding opening formed in the bottom member 29.

The operation of the described printers' furniture piece is apparent from the above description.

When the screw 47 is loosened, the members 10 and 11 can be conveniently moved relatively to each other, the serrations 45 sliding upon the projections 46. The serrations 45 may be provided with a suitable scale (not shown), which enables the user to set the relative distances of the surfaces 12 and 13 at will. However, the user can also insert the furniture piece inside the available space, and then proceed to move the portions 10 and 11 relatively to each other until the surfaces 12 and 13 engage the adjacent pieces.

It is apparent that this arrangement provides a most convenient expandable furniture piece which is suitable to fit very large, as well as comparatively small spaces.

When the desired relative positions of the members 10 and 11 have been set, the furniture piece is located in the selected position by screwing down the thumb screw 47.

FIGURE 4 shows in section a substantially similar furniture piece comprising members 10 and 11. In this construction the locking of the member 10 relatively to the member 11 is carried out by means of a cam lock comprising a cam disk 50 connected with a lever 51. The cam disk 50 is swingably mounted upon a support 52, which extends through the bottom portion 28, the slot 44, and the bottom portion 29. The lower end of the support 52 is provided with a head 53.

It is apparent that when the lever 51 is located in the illustrated horizontal position, the cam member 50 will press against the bottom portion 28 and will firmly clamp the members 10 and 11. By swinging the lever 51 upwardly to a vertical position, pressure upon the bottom portion 28 is released and the members 10 and 11 may be conveniently moved relatively to each other.

In other respects the construction is the same as the one which was previously described.

The furniture piece shown in FIGURES 5 and 6 is particularly suitable for use when very narrow spaces are involved. The furniture piece comprises an outer member 60 having a registering end surface 61. An inner member 62 has a registering end surface 63 which is located at the end of a T-shaped head 64 provided with side surfaces 65 and 66, which are in alignment with the side surfaces 67 and 68 provided in the outer member 60.

The head 64 of the inner member 62 is connected with a body portion 69 which slides within a slot 70 provided in the outer member 60. As shown in FIG. 6, the slot 70 is substantially rectangular in shape and is open on one side. The inner member 62 has a side surface 71 which is flush with the side surfaces 72 and 73 of the outer member 60. The opposed edges 74 and 75 of the outer member 60 are provided with uniformly spaced projections or serrations 76 and 77, respectively. These serrations are preferably spaced at the distance of a pica or any other suitable unit, and they cooperate with correspondingly spaced recesses 78 and 79 provided at the opposed edges

of the elongated portion 69 of the inner member 62. The serrations 76 and 77 and/or the recesses 78 and 79 may be provided with a suitable scale for the convenience of the user.

5 The inner and outer members 60 and 62 may be provided with a suitable clamping device which is not shown in the drawing.

In operation the user will pull the inner member 62 relatively to the outer member 60 until the surfaces 61 and 63 10 are at the desired distance from each other. In the course of the sliding movement, the serrations 76 and 77 will somewhat impede the sliding movement without preventing it, and the two members 60 and 62 may be conveniently set in a desired position which will correspond to 15 the required length.

It is apparent that the examples shown above have been given solely by way of illustration and not by way of limitation, and that they are capable of many variations and modifications within the scope of the present invention. All such variations and modifications are to be included within the scope of the present invention.

What is claimed is:

1. Printers' furniture, comprising an elongated outer member having a registering outer end surface, an inner 25 sliding surface, two inner side surfaces located on both sides of said inner sliding surface, and an inner end surface, and an elongated inner member comprising an end portion having an outer registering surface, said inner member further comprising a body portion slideable relatively to the inner surfaces of said outer member and having an inner sliding surface located opposite the inner 30 sliding surface of said outer member, and spaced serrations upon an inner side surface of said outer member and an opposed surface of the body portion of said inner member, 35 said serrations being adapted to interengage in different relative positions of the outer and inner members for setting the distance between said registering surfaces.

2. Printers' furniture, comprising an elongated outer 40 member having a registering outer end surface, recessed sides, and two parallel bottom portions having opposed grooves, an elongated inner member comprising side portions sliding in said recessed sides of the outer member, a bottom sliding between said bottom portions of the outer 45 member and having ridges extending within said grooves, and a registering outer end surface, and means locking said inner member in one of a plurality of positions relatively to said outer member.

3. Printers' furniture, comprising an elongated outer 50 member having a registering outer end surface, recessed sides, and two parallel bottom portions, and an elongated inner member comprising side portions sliding in said recessed sides of the outer member, a bottom sliding between 55 said bottom portions of the outer member and a registering outer end surface, and spaced serrations upon the bottom of said inner member and an opposed surface of a bottom portion of said outer member, said serrations being adapted to interengage in different relative positions of the outer and inner members for setting the distance between said registering surfaces.

4. Printers' furniture, comprising an elongated outer member having a registering outer end surface, recessed sides, and two parallel bottom portions, an elongated inner member comprising side portions sliding in said recessed sides of the outer member, a bottom member and a 65 tween said bottom portions of the outer member and a registering outer end surface, the bottom of said inner member having an elongated slot, and a lock extending through said slot and through openings formed in the 70 bottom portions of said outer member for locking said inner member in one of a plurality of positions relatively to said outer member.

5. Printers' furniture, comprising an elongated outer member having a registering outer end surface, recessed 75 sides, and two parallel bottom portions, an elongated in-

inner member comprising side portions sliding in said recessed sides of the outer member, a bottom sliding between said bottom portions of the outer member and a registering outer end surface, the bottom of said inner member having an elongated slot, and a screw extending through said slot and through openings formed in the bottom portions of said outer member for locking said inner member in one of a plurality of positions relatively to said outer member.

6. Printers' furniture, comprising an elongated outer member having a registering outer end surface, recessed sides, and two parallel bottom portions, an elongated inner member comprising side portions sliding in said re-

cessed sides of the outer member, a bottom sliding between said bottom portions of the outer member and a registering outer end surface, the bottom of said inner member having an elongated slot, and a cam lock extending through said slot and through openings formed in the bottom portions of said outer member for locking said inner member in one of a plurality of positions relatively to said outer member.
